INTERLOCKED BLADE SHROUDING

Harvey W. Welsh, Indianapolis, Ind., assignor to General Motors Corporation, Detroit, Mich., a corporation of Delaware

Filed Aug. 14, 1957, Ser. No. 678,090

6 Claims. (Cl. 253—77)

My invention relates to shrouded blade structures for the rotors of fluid-dynamic machines such as axial-flow compressors and turbines.

Certain advantages of providing shrouding on the tips of compressors and turbine rotor blades have long been appreciated. The provision of a satisfactory shrouded blade structure involves substantial difficulties, however, particularly in the case of compressor blading of low hub radius to tip radius ratio. In such a case, the blades may be closely spaced at the hub, but are widely spaced at the tip. Since such machines may be of considerable diameter and rotate at high speed, there is a high centrifugal force on the shroud. My invention is directed primarily to the provision of a suitable lightweight shroud structure which will not put a heavy radial load on the blades and yet which is sufficiently rigid that it will not bow out to a harmful extent between the blades, and to a simple, lightweight, reliable, and readily applied attachment for the shroud which makes it practicable to remove the shroud for replacement of damaged blades.

The blade shrouding structure of the present invention represents a different approach to the problem of shrouding rotor blades from that described in my U.S. Patent No. 2,963,272.

The nature of the invention and the advantages thereof will be apparent to those skilled in the art from the succeeding detailed description of the preferred embodiment of the invention and the accompanying drawings thereof.

Figure 1 is a fragmentary sectional view of the rotor of an axial-flow compressor taken on a plane normal to the axis of the rotor.

Figure 2 is a fragmentary exterior view of the rotor with parts cut away and in section.

Figure 3 is a sectional view taken on the plane indicated by the line 3—3 in Figure 2.

Figure 4 is a view of the blade tip.

Figure 5 is a sectional view through the shroud taken in the plane indicated by the line 5—5 in Figure 1.

Figure 6 is an exploded view, with parts cut away, illustrating the connection of the shroud to the blade.

Figure 7 is a partial elevation view of a compressor rotor.

The structure of the rotor is illustrated generally in Fig. 7. The details of the rotor wheel and blade root are, of course, immaterial to this invention. Fig. 7 shows a rotor wheel or disk 8 in which are engaged the roots 9 of blades 10, to the tips of which is attached a shroud composed of segments 12.

Referring to Figure 1, the rotor includes a ring of blades 10 which may be of the usual airfoil contour indicated in Figure 2, or any form suited to the particular compressor. The blades extend from the rotor wheel or disk 8. A shroud structure extending around the tips of the blades is defined by a number of shroud segments 12 preferably equal in number to the number of blades, each segment extending from the tip of one blade to the tip of the next with the ends of the segments overlapping at the blade and being secured to the blade tip. The shroud

2

segment is principally a sheet metal structure, as most clearly shown by Figure 5. It comprises an inner arcuate strip 13, a hat section strip 14, the marginal flanges of which are brazed or spotwelded to the edges of the strip 13, and a channel section strip 16. The base of the channel is preferably spotwelded to the base of the hat section so that the flanges 17 of the channel strip extend outwardly to provide labyrinth seal flanges which closely approach the case of the compressor to minimize leakage across the tips of the blades.

A generally T-shaped block 18 is welded or brazed in the space between the strips 13 and 14 at one end of the segment. The leading and trailing edge portions of the strips are cut away to conform to the shape of the block, the strips and block defining a tongue 19 extending from the end of the segment. Two L-shaped blocks 21 and 22 are similarly mounted in the space between the strips 13 and 14 at the other end of the segment. The central part of the webs of the strips 13, 14, and 16 is cut out so that this end of the shroud defines two tongues 23 and 24 which extend on each side of the tongue 19 when the shroud segments are mounted on the blades. The tongue 19 fits closely between the tongues 23 and 24.

An undercut or dovetail slot 26 extends spanwise of the blade through the three tongues 19, 23, and 24. The portions of the slot in the two segments are aligned when the shroud is assembled. The walls of the slots define ledges 27 facing outwardly from the rotor.

Each blade 10 includes a head portion 28 extending chordwise of the blade, preferably for about three-fifths of the chord of the blade. As will be clearly apparent in Figures 3 and 4, this head is of H-shaped cross-section having slots 29 in the sides of the head. The outer surfaces of the slots provide abutments 31 facing inwardly toward the rotor. The surfaces 32 of the head are adapted to engage the inner radial wall 33 of the slot 26 with a slight clearance so that the shroud segments can readily be dropped over the head of the blade.

As will be apparent from the drawings, the tip of the blade is skewed with respect to the axial direction through the rotor so that the head 28, slot 26, and, in general, the structures defining the tongues 19, 23, and 24, are similarly skewed.

To assemble the shroud segments on the blades, the overlapping ends of two adjacent segments are dropped over the head of the blade with the tongue 19 extending between the tongues 23 and 24. The shrouds are held in place against centrifugal force, which would tend to move them outwardly, by two keys 34 which are L-shaped in cross-section, one flange of the key entering the slot 29 in the blade head and the other flange extending radially outward between the blade head and the radial walls of slot 26. As will be apparent, these keys engage the ledges defined by the walls of the slot and the abutments defined by the blade head and provide a very strong and positive connection between the blade and the shroud.

The keys 34 are retained against displacement lengthwise of the keys by a sheet metal retainer 36 which extends through the slot 26 in a clearance space between the tip of the blade head and the base of the slot 26. As will be apparent from Figures 1 and 3, this retainer is slightly V-shaped so that it is a spring fit in the space to prevent the retainer from rattling or shifting, but the retainer is easy to install, as close clearances are unnecessary. Two tabs or heads 38 are provided on each end of the retainer. The tabs, at one end at least, are in the plane of the major portion of the retainer until it has been inserted in the slot 26. These tabs are then bent inwardly as shown in the drawings. The tabs overlie both a portion of the end of the key 34 and a portion of

the end of the blade head 28 so that neither the retainer nor the keys can move chordwise of the blade.

It will be apparent from the foregoing that the shroud is easily installed on the blades after they have been mounted in the rotor. If it should become necessary to replace a blade, the shroud may be cleared from the blade by removing only the two segments which attach to it. These may be easily removed by bending up the tabs 38, pushing out the retainer and the keys, and lifting the segments off the blades.

An important advantage of the structure according to the invention is the positive, rigid and easily installed connection between the blade and the shroud. Another important advantage is the rigid but lightweight structure of the shroud segment which is formed from sheet metal to provide a box section, as illustrated in Figure 5, which is very rigid for its weight and thus will resist any substantial bowing due to the effect of centrifugal force. Because the structure is light, it puts a minimum centrifugal load on the blades.

The detailed description of the preferred embodiment of the invention for the purpose of explaining the principles thereof is not to be considered as limiting or restricting the invention, as many modifications may be made by the exercise of skill in the art without departing from the principles of the invention.

I claim:

1. A shrouded turbomachine rotor structure comprising, in combination, a rotor, a ring of blades extending from the rotor, a shroud mounted on the tips of the blades, the shroud comprising a number of segments mounted end-to-end to provide a shroud around the tips of the blades, each shroud segment having two tongues spaced chordwise of the blade at one end and a tongue at the other end extending between the two tongues at the said one end of the adjacent shroud segment, the tongues having an undercut slot extending chordwise of the blade providing ledges facing outwardly from the rotor, each blade having a head on the tip thereof extending chordwise of the blade, the head being dimensioned so as to be insertable radially into the slot and defining a shoulder facing inwardly toward the rotor at each face of the blade, and keys insertable by movement lengthwise of the slot engaging between the shoulders and the ledges retaining the segments on the blades.

2. A shrouded turbomachine rotor structure comprising, in combination, a rotor, a ring of blades extending from the rotor, a shroud mounted on the tips of the blades, the shroud comprising a number of sheet metal box-section segments mounted end-to-end to provide a shroud around the tips of the blades, each shroud segment having two tongues spaced chordwise of the blade at one end and a tongue at the other end extending between the two tongues at the said one end of the adjacent shroud segment, the tongues having an undercut slot extending chordwise of the blade providing ledges facing outwardly from the rotor, each blade having a head on the tip thereof extending chordwise of the blade, the head being dimensioned so as to be insertable radially into the slot and defining a shoulder facing inwardly toward the rotor at each face of the blade, and keys insertable by movement lengthwise of the slot engaging between the shoulders and the ledges retaining the segments on the blades.

3. A shrouded turbomachine rotor structure comprising, in combination, a rotor, a ring of blades extending from the rotor, a shroud mounted on the tips of the blades, the shroud comprising a number of segments mounted end-to-end to provide a shroud around the tips of the blades, each shroud segment having two tongues spaced chordwise of the blade at one end and a tongue at the other end extending between the two tongues at the said one end of the adjacent shroud segment, the tongues having an undercut slot extending chordwise of the

the blade providing ledges facing outwardly from the rotor, each blade having a head on the tip thereof extending chordwise of the blade, the head being dimensioned so as to be insertable radially into the slot and defining a shoulder facing inwardly toward the rotor at each face of the blade, and two keys slidably mounted in the slots in the tongues extending between and engaging the shoulders of the blade and the ledges of the shroud segment tongues.

10 4. A shrouded turbomachine rotor structure comprising, in combination, a rotor, a ring of blades extending from the rotor, a shroud mounted on the tips of the blades, the shroud comprising a number of segments mounted end-to-end to provide a shroud around the tips of the blades, each shroud segment having two tongues spaced chordwise of the blade at one end and a tongue at the other end extending between the two tongues at the said one end of the adjacent shroud segment, the tongues having an undercut slot extending chordwise of the blade providing ledges facing outwardly from the rotor, each blade having a head on the tip thereof extending chordwise of the blade, the head being dimensioned so as to be insertable radially into the slot and defining a shoulder facing inwardly toward the rotor at each face of the blade, two keys slidably mounted in the slots in the tongues extending between and engaging the shoulders of the blade and the ledges of the shroud segment tongues, and a retainer extending through the slot and having tabs adapted to overlie both ends of the keys and the ends of the head of the blade to retain the keys against chordwise displacement.

15 5. A shrouded turbomachine rotor structure comprising, in combination, a rotor, a ring of blades extending from the rotor, a shroud mounted on the tips of the blades, the shroud comprising a number of segments mounted end-to-end to provide a shroud around the tips of the blades, each shroud segment having two tongues spaced chordwise of the blade at one end and a tongue at the other end extending between the two tongues at the said one end of the adjacent shroud segment, the tongues having an undercut slot extending chordwise of the blade providing ledges facing outwardly from the rotor, each blade having a head on the tip thereof extending chordwise of the blade, the head being dimensioned so as to be insertable radially into the slot and defining a shoulder facing inwardly toward the rotor at each face of the blade, two keys of L-shaped cross-section slidably mounted in the slots in the tongues extending between and engaging the shoulders of the blade and the ledges of the shroud segment tongues, and a retainer extending through the slot and having tabs adapted to overlie both ends of the keys and the ends of the head of the blade to retain the keys against chordwise displacement.

20 6. A shrouded turbomachine rotor structure comprising, in combination, a rotor, a ring of blades extending from the rotor, a shroud mounted on the tips of the blades, the shroud comprising a number of segments mounted end-to-end to provide a shroud around the tips of the blades, each shroud segment having two tongues spaced chordwise of the blade at one end and a tongue at the other end extending between the two tongues at the said one end of the adjacent shroud segment, the tongues having an undercut slot extending chordwise of the blade providing ledges facing outwardly from the rotor, each blade having a head on the tip thereof extending chordwise of the blade, the head being dimensioned so as to be insertable radially into the slot and defining a shoulder facing inwardly toward the rotor at each face of the blade, two keys slidably mounted in the slots in the tongues engaging the shoulders of the blade and the ledges of the shroud segment tongues, and a retainer extending through the slot between the head of the blade and the base of the slot and having heads adapted to overlie both ends of the keys and the ends

of the head of the blade to retain the keys against chord-wise displacement, the retainer portion extending through the slot being non-planar to provide resilient engagement with the head of the blade and the base of the slot.
